[57] **CLAIM**

The ornamental design for a terminal console, substantially as shown and described.

DESCRIPTION

FIG. 1 is a front orthogonal view of the terminal console showing my new design;

FIG. 2 is a top plan view thereof on an enlarged scale;
FIG. 3 is a front elevational view thereof on an enlarged scale;

FIG. 4 is a right side elevational view thereof on an enlarged scale;

FIG. 5 is a left side elevational view thereof on an enlarged scale.

The keys are shown in broken lines in FIGS. 1 and 2 for illustrative purposes only.

F/G. 2.

FIG. 3.
